(57) **CLAIM**

The ornamental design for eye glasses for virtual display device, as shown and described.

DESCRIPTION

FIG. 1 is a front view of eye glasses for virtual display device bearing the design;

FIG. 2 is a back view thereof;

FIG. 3 is a left side view thereof;

FIG. 4 is a top view thereof;

FIG. 5 is a bottom view thereof;

FIG. 6 is a top-right-back perspective view thereof;

FIG. 7 is a left side view thereof in a used state; and,

FIG. 8 is a bottom view thereof in the used state.

The broken lines shown in the drawings form no part of the claimed design.
